CLAIM

The ornamental design for an electrophoresis buffer pad, as shown and described.

DESCRIPTION

(30) **Foreign Application Priority Data**

Nov. 26, 2013 (EM) 002352021-0001

(51) **LOC (10) Cl.** **24-01**

(52) **U.S. Cl.**

USPC **D24/233**

(58) **Field of Classification Search**

USPC D24/233, 216, 224, 231–232, 127–128;
204/600, 602, 615–616, 619–620, 456,

FIG. 1 is a front perspective view of an electrophoresis buffer pad according to the design.

FIG. 2 is a front view thereof.

FIG. 3 is a bottom view thereof.

FIG. 4 is a top view thereof.

FIG. 5 is a back view thereof.

FIG. 6 is a left side view thereof; and,

FIG. 7 is a right side view thereof.
